UNITED STATES PATENT OFFICE.

JOHN J. TATUM, OF BALTIMORE, MARYLAND.

DRAFT-RIGGING.

1,279,175.

Specification of Letters Patent. Patented Sept. 17, 1918.

Application filed November 15, 1912. Serial No. 731,625.

To all whom it may concern:

Be it known that I, JOHN J. TATUM, a citizen of the United States, residing in the city of Baltimore and State of Maryland, have 5 invented certain new and useful Improvements in Draft-Rigging, of which the following is a specification.

The object of my invention is to provide a hood or other receptacle pivoted on the front end of a draft gear yoke or casing constructed to receive and be secured to the rear end of a draw bar; and with this and other objects in view my invention consists of the parts and combination of parts as 15 will be more fully hereinafter pointed out.

In the drawings—

Figure 1 is a top plan view of a car underframe (parts being broken away), with my invention in position.

Fig. 2 is a vertical section of Fig. 1 taken to one side of the head and yoke.

Fig. 3 is a perspective view of a draft yoke with my improved hood attached thereto.

Fig. 4 is a perspective view of the yoke shown in Fig. 3.

Figs. 5, 6, 8 and 9 are perspective views of yokes showing different forms of attaching means.

Fig. 7 is a perspective view of a yoke and hood showing another form of joint between them.

Fig. 10 is a detail view of a draw bar.

The reference numeral 1 designates a 35 bolster, 2 an end sill, and 3 the center or draft sills of a car between which a draft gear 4 with the front and rear followers 5 and 6 are positioned, all of which may be of any approved pattern.

40 The front ends of the draft yoke or casing 7 are provided on their outer faces with a lug 8 having an arcuate bearing face 9 which is undercut as at 10 on a bevel as more clearly shown in Fig. 4.

45 The hood 11 is provided with arcuate bearing seats 12 in its upper and lower front edges beveled forwardly and constructed to receive the lugs 8 on the yoke whereby the hood is pivotally swung on the forward ends 50 of the draft yoke or casing. The hood is provided with key ways 13 and 14 through which a key 15 is adapted to pass to lock the rear end of the draw bar 16 in said hood; the draw bar having a key way 55 through its rear end which registers with

the key ways 13 and 14 of the hood, whereby the draw bar is swingingly mounted on the forward end of the draft yoke or casing. The key 15 also passes through the draft 60 sills of the car.

In Fig. 5 I have shown the bearing 17 on the yoke or casing as concaved, just the reverse to that shown in Fig. 4.

In Fig. 6 I show the bearing in the form of a boss 18 constructed to engage a hole 65 made in the top and bottom of the hood.

In Fig. 7 I show the hood 19 secured to the yoke or casing 20 by means of a pivot post or rivet 21 at the top and bottom. In this construction I provide an arcuate slot 70 22 in the top and bottom of the hood through which a pin 23 projects from the yoke or casing 20 thereby limiting the swing of the hood as will be understood.

My invention provides free radial or 75 swinging movement of the draw bar of a car without imposing strain or stress on the draft rigging or the car, reduces train resistance and permits of hauling longer trains and greater tonnage with minimum 80 locomotive energy and fuel consumption.

By my invention I also reduce rail wear, wheel flange wear, thus giving a greater factor of safety to both life and property. I also reduce to a minimum, wear on the coupler and on the draw bar.

The pivoted swinging hood provides a flexible carrier or mounting between the draw bar and the draft gear and underframing 90 of the car which enables a train to pass the sharpest curves without reducing the engaging surfaces between the yoke and draw bar, and without imposing a shearing strain on the flange of the wheel and keeping uniform form bearing on key in the slots of the hood. 95

My invention may be applied to many types of existing draft gears and draw bars without changing the construction thereof, therefore a railroad may adopt my invention without discarding its standard type of 100 draw bar and its standard type of draft gear, it being only necessary to pivotally mount the hood on the forward end of the yoke or casing of the draft gear.

The bolts 24 serve the purpose of maintaining the yoke arms in place, in the event of a draw bar being used with a rear end too small to perform this function.

In Fig. 8, I have shown the yoke provided with an integral back follower.

110

In Fig. 9, the forward ends of the arms are turned outwardly and rearwardly to form bearings for the hood.

In Fig. 10, I have illustrated the draw bar 5 as being provided with a triangular-shaped key way.

As will be seen from the above description, when a train equipped with my improved hood is pulling around a curve, the key is bearing on the front of the slot on both 10 sides of the hood.

What I claim is:

1. In a draft gear, a yoke, a coupler bar receptacle swingingly mounted on the said 15 yoke and slidably connected to the yoke when in assembled position.

2. In a draft rigging, a yoke which consists of a hood and a loop having two free arms the ends of which are detachably 20 secured to said hood and pivotally and axially slidably connected thereto.

3. In a draft rigging for cars, the combination with the yoke, of a draw bar hood pivotally and slidably mounted on the forward 25 end of said yoke.

4. In a draft rigging for cars, the combination with a yoke, of a hood pivotally and slidably mounted on the forward end of the yoke, and means for securing the hood to 30 the draw bar whereby the draw bar has pivotable and slidable movement relative to the yoke.

5. In a draft rigging for cars, a casing, a draft gear, a hood swingingly and slidably 35 mounted on the forward end of said casing and provided with elongated key ways through its sides.

6. In a draft rigging for cars, a casing 40 for a draft gear, a hood swingingly mounted on the front end of said casing and provided with elongated key ways through its side walls, a draw bar the rear end of which is positioned in said hood, a key way through the rear end of said bar, and a key of width 45 less than the length of the elongated key ways of the hood, whereby the draw bar and key may move inwardly independently of the casing.

7. In a draft rigging, the combination

with a draft gear casing, of a hood mounted 50 on the forward end of the casing to move axially and radially of the casing.

8. The combination with shock absorbing draft devices, of a U-shaped yoke having 55 bearings at its two front ends, a hood of greater dimension than said yoke loosely mounted on the yoke so that it may move lengthwise of the yoke and swing radially thereon, the outward movement of the hood being limited by said bearings. 60

9. The combination with shock absorbing draft devices, of a U-shaped yoke having stops at its free ends, a hood slidably and swingingly mounted on said yoke, and a 65 coupler to which said head is keyed.

10. In a draft rigging, the combination with a yoke strap, of a hollow head, a draw bar, and a key extending through the draw bar and the sides of the hollow head, said head being movable axially and radially 70 relatively to the yoke strap when in operative position.

11. In a draft rigging the combination with shock absorbing draft devices, of a U-shaped yoke having stops at its free ends, a 75 hood slidably and swingingly mounted on said yoke, and seats on said yoke to engage said stops when the hood is at the limit of its outward movement, and a coupler to which said head is keyed.

12. In a draft gear, a yoke, means swingingly mounted on the forward end of said yoke, and slidably connected to the yoke when in assembled position with the rear end of a coupler, a key to enter alined openings in said means and in the rear end of the coupler to secure said means and coupler together, a curved bearing on one of the meeting faces of said means and said yoke to permit of a laterally swinging movement 80 of said means to accommodate the swinging movement of the draw bar. 85

In testimony whereof I affix my signature in presence of two witnesses.

JOHN J. TATUM.
